Attorney.

UNITED STATES PATENT OFFICE

133,056

DESIGN FOR A BADGE OR THE LIKE

James Gilbert Bullard, McAlester, Okla., assignor of one-half to W. A. Ley, North McAlester, Okla.

Application March 23, 1942, Serial No. 106,276

Term of patent 3½ years

To whom it may concern:

Be it known that I, James Gilbert Bullard, a citizen of the United States and resident of McAlester, in the county of Pittsburg and State of Oklahoma, have invented a new, original, and ornamental Design for a Badge or the like, of which the following is a specification, reference being had to the accompanying drawing, forming part thereof.

Figure 1 is a plan view of a badge or the like, showing my new design, and

I claim:
The ornamental design for a badge or the like, as shown.

JAMES GILBERT BULLARD.
